UNITED STATES PATENT OFFICE.

JOSEPH N. ROYAL, OF BUFFALO, NEW YORK, ASSIGNOR TO F. N. BURT COMPANY, LIMITED, OF TORONTO, CANADA, A CORPORATION OF ONTARIO, CANADA.

DESIGN FOR A BOX.

Application filed December 9, 1926. Serial No. 19,997. Term of patent 14 years.

To all whom it may concern:

Be it known that I, JOSEPH N. ROYAL, a citizen of the United States, residing at Buffalo, county of Erie, State of New York, have invented a new, original, and ornamental Design for a Box, of which the following is a specification, reference being had to the accompanying drawing, forming a part

Fig. 1 is a front view of a box showing my new design.

Fig. 2 is a side view of the same.

I claim:

The ornamental design for a box, as shown.

JOSEPH N. ROYAL.
